UNITED STATES PATENT OFFICE

EDWARD C. LINDFELT, OF DES MOINES, IOWA

HANDBALL GLOVE

Application filed June 17, 1929. Serial No. 371,520.

My invention relates particularly to gloves used in playing handball, and has to do particularly with a peculiar novel structure of the back of a glove, whereby adequate ventilation may be secured without effecting the shapeliness or strength of the glove.

With this and other objects in view, my invention consists in the construction, arrangement and combination of the various parts 10 of my handball glove, whereby the objects contemplated are attained, as hereinafter more fully set forth, pointed out in my claims, and illustrated in the accompanying drawings, in which:

15 Figure 1 is a rear elevation of a handball glove embodying my invention.

Figure 2 is a side elevation of the same, parts being shown in vertical section; and

20 Figure 3 is a view similar to that illustrated in Figure 2, showing the glove in a different position.

In making gloves like handball gloves, which are intended for wear by athletes engaged in vigorous games, it is highly desirable to provide adequate ventilation.

It has been found quite difficult to accomplish this purpose without detracting from the fit of the glove by taking out material in making holes, with the result that the glove 30 would stretch out of shape.

Glove leather, such as horsehide, goatskin and sheep's hide, will stretch in one direction, but will not stretch very much in the other direction.

35 It is the general practice to arrange the leather in the back of the glove, so that the stretch of the glove is transverse.

I have tried cutting a number of large 40 round holes out of the glove, but this was a complete failure. Enough material was removed so that the glove would stretch laterally too much and would allow too much wrinkling in the front or palm of the glove.

45 This was very undesirable in a handball glove. Then I conceived the structure of the glove of the present application.

In the drawings, I have used the reference numeral 10 to indicate generally a handball glove having the thumb 12 and the fingers 14.

50 The back of the glove is indicated at 10a.

These gloves are ordinarily provided with two straps 16 and 17 secured at opposite sides of the wrist portion and adapted to be adjustably fastened together by means of a sliding buckle 18.

My present invention involves cutting in the back 10a of the glove a series of rows of slits. The slits are indicated at 20. The rows are arranged lengthwise of the glove, as at A, B and C. By this arrangement, it is seen that there is left between the rows A and B, and the rows B and C, longitudinal strips 22.

The respective slits 20 are also arranged in rows transversely of the glove, as indicated at a, b, c, etc. This leaves strips 24 of uncut leather crosswise of the back 10a of the glove 10.

The uncut strips 22 run in the direction in which the glove leather has little or no stretch.

The strips 24 run in the direction in which the glove leather has some natural stretch.

By arranging the slits in this way, no material is cut from the glove, and the slits do not change the natural and normal action of the glove back 10a. There will be no stretch lengthwise of the glove, because of the strips 22, and the sidewise or transverse stretch will be unchanged because of the strips 24. Yet these slits 20 allow adequate ventilation.

When the glove is on the hand, and the fingers are partially flexed, the slits open and allow the free passage of air.

The opening and closing of the fingers gives a sort of bellows action which contributes to adequate ventilation.

I have tried a great number of experiments to try to secure proper ventilation without interfering with the normal stretch of the glove back and have discovered that the present arrangement is satisfactory while every other arrangement I have tried has been unsuccessful.

For instance, I tried cutting large round holes and found that this removed so much material from the glove that it stretched transversely too much as above stated.

It would also stretch lengthwise where the holes were cut in the back.

I also tried making slits which were stag-

gered instead of arranged in rows in both directions as herein explained, and found when this was done, that the glove would stretch out of shape in a very short time.

5 It has been common practice in handball gloves to put in the back in the wrist portion a V-shaped gore of leather, which was softer than the main portion of the glove back. I have entirely omitted this V-shaped gore, 10 and have cut from the wrist into the glove back a U-shaped opening, indicated at 26.

I find that this is much more desirable than the V-shaped gore. Where the gore is employed, the soft leather doubles over when 15 the straps are pulled up, leaving a lump on the back of the hand. This is entirely avoided by cutting the U-shaped opening 26 in the back 10a of the glove as clearly shown in Figure 1. When such an opening is cut it 20 is necessary to provide a somewhat rigid bead or stiffening member 27 to prevent rolling of the edges of the opening 26. It may here be noted that this particular combination of U-shaped opening and stiffening 25 bead 27 cause the lowermost portions of the U-shaped opening to approach each other when the buckle 18 is manipulated for tightening the glove on the hand.

Such drawing up of the glove for the purpose of causing the glove to fit the wearer's hand produces a very noticeable buckling of the back 10a adjacent the rounded upper end of the U-shaped opening 26. The upper end of the opening also is quite spread apart 35 as clearly illustrated and therefore provides a large ventilation opening caused by the packing of glove adjacent the upper end of the opening, the slits 20 merely providing additional ventilation if it is desirable to 40 make the glove with the slits. The action of the glove when the wearer's hand is flexed produces an alternate inflow and outflow of air through the opening 26 as shown by the arrows 26a.

45 I have therefore provided a glove which will afford proper ventilation and which will not result in the glove being stretched out of shape. This is done by arranging the slits as shown. By this arrangement, I take advantage of the natural tendency of the leather to stretch in one direction and not to stretch in the other.

I claim as my invention:

50 1. In a glove for athletic use, a leather back portion arranged in the glove in such manner that its greater tendency to stretch is transverse, said portion having a plurality of transverse rows of transversely elongated slits, which slits are likewise arranged in 55 rows lengthwise of the glove.

55 2. In a glove for athletic use, a leather back portion arranged in the glove in such manner that its greater tendency to stretch is transverse, said portion having a plurality of transverse rows of transversely elongated

gated slits, which slits are likewise arranged in rows lengthwise of the glove, said glove having means for tightening it around the wrist of a wearer.

3. In an athletic glove, a back portion 70 made of leather, said back portion being provided with a plurality of slits arranged with their long axes across the grain of the leather and in the direction of its greater tendency to stretch, said slits being arranged 75 in rows transversely and lengthwise of said leather portion.

Des Moines, Iowa, May 23, 1929.

EDWARD C. LINDFELT.
